UNITED STATES PATENT OFFICE.

JAMES P. RATIGAN, OF WALNUT PARK, CALIFORNIA.

CABLE HOOK.

Application filed November 13, 1926. Serial No. 148,161.

This invention relates to cable hooks and, more especially, to a type of cable hook suitable for connecting a cable to the beam hanger of a pumping apparatus, though it is to be understood that the invention is not limited to this use. This invention is a division of my copending application for patent, filed April 13, 1925, Serial No. 22,768.

More specifically, the invention relates to a cable hook constructed of opposed members positioned so as to permit of a cable being placed from one side on one of the members and from the opposite side on the other member.

Other objects and advantages may appear in the subjoined detailed description.

The accompanying drawings illustrate the invention.

Figure 1 is a broken side elevation of a pumping apparatus having as a part thereof a cable hook embodying the invention. The walking beam is shown partly in section.

Figure 2 is an enlarged edge view of the cable hook, fragments of the means for suspending the cable hook also being shown.

Figure 3 is an elevation of Fig. 2 from the left thereof.

Figure 4 is an elevation of the cable hook on a smaller scale than shown in Fig. 3, with the hook members in open position to permit of removal or replacement of the cable.

Figure 5 is a perspective view of one of the hook members.

Referring first to the apparatus shown complete in Fig. 1, there is an operating member 6 which, in this instance, is in the form of a walking beam. The member 6 is pivoted at 7 to a Samson post 8. Suspended from one end of the member 6 is a beam hanger, indicated in general by the character 9. This beam hanger may be of any suitable construction and, in this instance, is of a type that effects rotation of the polish rod, a fragment of which is indicated at 10. It is to be understood that the beam hanger may be of the nonrotating type if desired, since the type of beam hanger has no particular bearing upon the present invention. The beam hanger shown is the subject of my copending application for patent filed April 13, 1925, Serial No. 22,768.

My invention is suspended from the beam hanger 9 and is indicated in general by the character 11, and engaged by the cable hook

polish rod grip 13 in which the polish rod 10 is clamped.

The cable hook 11 is constructed as follows: To the beam hanger 9 is connected a pivot pin 14 and mounted to swing on this pin is a pair of hook-shaped members 15, the open sides of the hooks being turned toward a plane intersecting both hooks when said hooks are closed together, as in Figs. 1, 2 and 3 and said plane being normal to the axis of the pivot pin. The members 15 have their shanks or upper portions 16 in overlapping relation sideways. The lower, grooved portions 17 of the members 15 are in overlapping relation edgewise. The cable 12, when engaged with the hook members and connected with a load, prevents swinging of the hook members away from one another. When the cable is relieved of its load, the hook members may be swung away from each other, as in Fig. 4, thus spacing their grooved portions sufficiently to admit of the entrance or exit of the bight of the cable. When the hook members 15 are closed, as in Figs 2 and 3, the cable 12 rests in both hook members so that each hook member prevents removal of the cable from the other member. The reason for this is that the hook members are opposed or complementary to each other with the backs of the hook members on opposite sides of the cable.

From the foregoing, it will be readily understood that the invention broadly comprises opposed hook-shaped members, provided with cable grooves on their adjacent faces, and the backs of the hooks being on opposite sides of the cable. It is not absolutely necessary that the hook members be in pivotal relation, but the pivotal construction facilitates entrance and exit of the cable to the grooves of the hook members.

If desired, one of the hook members may be provided with a stud 18 adapted to engage in a socket 19 in the other hook member when the hook members are in closed position, the stud and socket being on the adjacent edges of the hook members. The stud and socket will resist any tendency to thrusting of the hook members away from one another in directions at right angles to a plane intersecting both hook members.

It may be of advantage in some instances to provide a means for preventing any tendency to jumping upwardly of the cables in the hook members, and for this reason I have

55 is a cable 12 which connects with a suitable

- shown each hook member provided on its outer edge with a pair of ears 20, the ears of each pair being on opposite sides of the cable. Passing through each pair of ears 5 is a cotter pin 21, and thus, after the cable has been placed in the hook members and the cotter pins have been placed in position, the cable will lie between the opposed hook members 15 and also between the cotter pins. 10 The foregoing will make clear the construction and operation of the invention, and the operation in brief is as follows: Assuming, for example, that the cable 12 is engaged by the hook members in the 15 manner depicted in Figs. 2 and 3, and that it is desired to detach the cable from said hook members, the cable will first be relieved of its load in a manner well understood in the art relating to well pumping apparatus, 20 and the hook members 15 will be swung away from one another to the open positions, as shown in Fig. 4, whereupon the cable will be lifted first out of the groove of one hook member and allowed to drop so as to pass 25 through the space between the open hook members, and the cable will then be lifted out of the groove of the other hook member. To replace the cable, the operations just described will be executed in reverse order. 30 I claim:—
1. A cable hook comprising a pivot pin, and a pair of hook members mounted on said pin, the open sides of the members being turned toward a plane intersecting both members and said plane being normal to the axis of the pivot pin. 35

2. A cable hook comprising a pair of hook members connected at their upper ends and positioned with their lower ends in overlapping relation edgewise of said members, 40 the backs of the hook members being on opposite sides of a cable engaged in the overlapping ends and said plane being normal to the axis of the pivot pin.

3. A cable hook comprising a pair of hook 45 members connected at their upper ends and positioned with their upper ends in overlapping relation in a plane at right angles to a plane intersecting both hooks, said hook members positioned with their lower ends in 50 overlapping relation edgewise of said members, the backs of the hook members being on opposite sides of a cable engaged in the overlapping ends.

4. A cable hook comprising a pair of hook 55 members, means movably connecting the upper ends of the hook members to permit spacing of the lower ends of said hook members, the open sides of the members being turned toward a plane intersecting both 60 members.

5. A cable hook comprising a pair of hook members constructed and arranged with their backs on opposite sides of a plane intersecting both members, said members having 65 their lower ends overlapping edgewise and permitting of the entrance of a cable from opposite sides.

Signed at Los Angeles, Calif., this 30 day of October, 1926.

JAMES P. RATIGAN.
